United States Patent Office.

CONYERS BUTTON, OF PHILADELPHIA, PENNSYLVANIA.

Design No. 3,575, dated July 6, 1869.

DESIGN FOR A SCARF-PATTERN.

The Schedule referred to in these Letters Patent and making part of the same.

To all whom it may concern:

Be it known that I, CONYERS BUTTON, of Philadelphia, county of Philadelphia, State of Pennsylvania, have originated a new Design for a Scarf; and I do hereby declare that the accompanying drawing, and the following explanation thereof, form a full, clear, and exact description of the said design.

In the drawing, the figure represents sufficient of a scarf to illustrate my design, which consists of a central stripe, A, on each side of which is a zigzag rib, B, the scarf having a plain edging, D.

Irrespective of the colors employed in carrying out my design,

I claim—

The design for a scarf, substantially as described, and as illustrated in and by the accompanying drawing.

In testimony whereof, I have signed my name to this specification, in the presence of two subscribing witnesses.

CONYERS BUTTON.
